[57] **ABSTRACT**

The present invention concerns new thiophosphoric acid amide esters of the formula:

wherein R_1 is alkyl of one to four carbon atoms,
 R_2 is alkyl of one to four carbon atoms,
 R_3 is alkyl of one to five carbon atoms, and
 X is hydrogen, chlorine or bromine.
The compounds are useful pesticides.

16 Claims, No Drawings

CIS-THIOPHOSPHORIC ACID AMIDE ESTERS

The present invention relates to new thiophosphoric acid amide esters of formula I,

wherein R_1 is alkyl of one to four carbon atoms, R_2 is alkyl of one to four carbon atoms, R_3 is alkyl of one to five carbon atoms, and X is hydrogen, chlorine or bromine, pesticidal compositions incorporating the compounds of formula I and processes for the production of the compounds.

Significant pesticidal activity of the compounds I is possessed by those compounds wherein the $-\text{CH}_3$ and $-\text{COOR}_3$ radicals are cis to one another in the crotonic acid radical. Thus, it is to be understood that definitions for the compounds I essentially contemplate compounds having said cis configuration, although compounds comprising a mixture of the cis form and a certain amount of the trans form are also contemplated. The configuration of compounds I is dependent on the configuration of the starting materials employed in the processes described below, and the process for the production of the starting materials described below result in a predominant proportion of compounds having the cis configuration.

According to the present invention a process for the production of a compound of formula I comprises

a. reacting a compound of formula V,

wherein R_1 , R_3 and X are as defined above, and Y is halogen,

with an amine of formula IV,

wherein R_2 is as defined above, in the presence of an acid acceptor, or

b. reacting a compound of formula VI,

wherein R_2 , R_3 , X and Y are as defined above, with a compound of formula III,

wherein R_1 is as defined above, and

Z is hydrogen or an alkali metal, in the presence of an acid acceptor when Z is hydrogen, and optionally in the presence of an acid acceptor when Z is an alkali metal.

5 Preferably Y is chlorine or bromine, and Z is hydrogen or sodium.

In one method of effecting process a) of the invention, a compound of formula IV and an acid acceptor such as triethylamine, trimethylamine, dimethyl aniline, diethyl aniline or sodium carbonate, are added at a temperature of between -20° and $+50^\circ\text{C}$, preferably between -10° and 0°C , to a compound of formula V in an inert solvent, e.g., an aromatic hydrocarbon such as toluene or xylene, a halogenated hydrocarbon such as

10 chlorobenzene or chloroform, or an ether such as dioxane, over a period of between one-half hour and 2 hours.

15 Preferably an equivalent amount of the compound of formula IV with respect to the compound of formula V is employed, and the amount of the acid acceptor is preferably such as to be equivalent with respect to the compound of formula V, for taking up the hydrohalic acid produced in the reaction. However, it will be appreciated that when a compound of formula IV itself is employed as acid acceptor, then the amount of the compound of formula IV is preferably two equivalents with respect to the compound of formula V.

20 The reaction mixture is stirred at room temperature over a period of between 10 and 20 hours. The solvent is subsequently removed in a vacuum at a bath temperature of between 20° and 50°C . The residue is distilled in a high vacuum. The pure compound of formula I is obtained as a colourless oil which can be distilled without decomposition.

25 In one method of effecting process b) of the invention, a compound of formula III and an acid acceptor such as triethylamine, trimethylamine, dimethyl aniline or diethyl aniline, are added at a temperature of between -20° and $+50^\circ\text{C}$, preferably between 0° and 20°C , to a compound of formula VI in an inert solvent, e.g., an aromatic hydrocarbon such as toluene or xylene, a halogenated hydrocarbon such as chlorobenzene or chloroform, or an ether such as dioxane, over 30 a period of between one-half hour and 2 hours.

35 In one method of effecting process b) of the invention, a compound of formula III and an acid acceptor such as triethylamine, trimethylamine, dimethyl aniline or diethyl aniline, are added at a temperature of between -20° and $+50^\circ\text{C}$, preferably between 0° and 20°C , to a compound of formula VI in an inert solvent, e.g., an aromatic hydrocarbon such as toluene or xylene, a halogenated hydrocarbon such as chlorobenzene or chloroform, or an ether such as dioxane, over 40 a period of between one-half hour and 2 hours.

45 Preferably an equivalent amount of the compound of formula III with respect to the compound of formula VI is employed, and the amount of acid acceptor is preferably such as to be equivalent with respect to the compound of formula VI, for the acceptance of displaced Y radicals.

50 The reaction mixture is subsequently stirred at 20°C over a period of between 20 and 100 hours, and the reaction mixture is then worked up in the usual manner, to yield the compound of formula I.

55 The compound of formula V employed as starting material in process a) above may be produced by reacting a compound of formula II,

wherein R_3 , X and Y are as defined above,

with a compound of formula III, optionally in the presence of an acid acceptor.

The resulting reaction mixture may be employed directly for reaction with the compound of formula IV in accordance with process a) above without isolation of the compound of formula V. One method of effecting process a) of the invention starting with the production of a compound of formula V and continuing through to the production of a compound of formula I, without isolation of the compound of formula V, comprises adding preferably at least one equivalent of a compound of formula III, at a temperature of between -20° and +50°C, preferably between -10°C and room temperature, to a compound of formula II in an inert solvent, e.g., an aromatic hydrocarbon such as toluene or xylene, a halogenated hydrocarbon such as chlorobenzene or chloroform, or an ether such as dioxane, over a period of between one-half hour and 2 hours, in the presence of an acid acceptor such as triethylamine, trimethylamine, dimethyl aniline or diethyl aniline.

Preferably the acid acceptor is present in an amount such as to be equivalent with respect to the compound of formula II, for the acceptance of displayed Y radicals.

Without isolation of the compound of formula V, produced by the preceding process, from the reaction mixture, a mixture of an amine of formula IV, preferably in an equivalent amount, with an acid acceptor, such as triethylamine, trimethylamine, dimethyl aniline or diethyl aniline, preferably tri-n-butyl amine, preferably also in an equivalent amount, is added at a temperature of between -20° and +50°C, preferably between -10°C and room temperature, over a period of between one-half hour and 2 hours to the reaction mixture. The reaction mixture is stirred at room temperature for about 20 hours. The reaction mixture is then worked up in the usual manner to yield the compound of formula I.

In an alternative method of effecting process a) of the invention commencing first with the production of a compound of formula V and then continuing through to the production of a compound of formula I, without isolation of the compound of formula V from the reaction mixture, a compound of formula II is reacted with a compound of formula III in a manner such as hereinbefore described, but in the absence of an acid acceptor. Subsequent reaction of the resulting compound still contained in the reaction mixture with a compound of formula IV may be effected by employing at least three equivalents of the compound of formula IV, which compound in addition to reacting with the compound of formula V, also serves as acid acceptor, by reacting with the hydrohalic acid produced during the overall reaction, including the reaction between the compounds of formulae II and III.

The production of a compound of formula VI, employed as starting material in process b) above for the production of a compound of formula I, may be effected by reacting a compound of formula II with a compound of formula IV, preferably in equivalent amounts, in the presence of an acid acceptor.

As already indicated, the compounds I of the invention essentially contemplate compounds wherein the -CH₃ and -COOR₃ radicals are cis to one another in the crotonic acid radical. This configuration, or a predominant proportion of compounds of formula I having this configuration (more than 80 % by weight) can be

achieved by preparing the above compounds of formula II in a specific manner. In general, the compounds of formula II may be produced by reacting a phosphoric oxy- or thio-chloride or bromide with a compound of formula VII,

VII

wherein R₃ and X are as defined above, or with a salt thereof, in the presence of an acid acceptor. The compounds of formula II predominantly have a cis configuration in the crotonic acid radical (i.e. the -CH₃ group is cis to the -COOR group) when an organic base, e.g., tri-n-butylamine or triethylamine, is used as acid acceptor. When, for example, sodium bicarbonate is used as acid acceptor, the portion of cis configuration in the crotonic acid radical of the compound of formula II is smaller than when triethylamine is used. When, for example, a sodium acetoacetic acid ester is used in place of the acetoacetic ester of formula VII and an acid acceptor, then compounds of formula II predominantly having the trans form in the crotonic acid radical are obtained. Thus, in order to obtain compounds of the desired high proportion of cis configuration, the acid acceptor employed in the production of compounds II needs to be, for example, tri-n-butylamine or triethylamine, and the sodium acetoacetic acid ester is normally not a suitable starting material in the production of compounds II.

In the case wherein a compound of formula II is required as a starting material in a process for the eventual production of a compound I according to process a) above, and involving the intermediate production of

a compound of formula V, the process may be effected by reacting a compound of formula VII with a phosphorus thiohalide, e.g., phosphorus thiochloride, in the presence of an acid acceptor, e.g., tri-n-butyl amine, and without isolating the resulting compound of formula II from the reaction mixture, adding thereto a compound of formula III together with an acid acceptor. After the reaction, without isolating the resulting compound of formula V, a compound of formula IV together with an acid acceptor are added to the reaction mixture under the conditions as hereinbefore described, and the reaction allowed to proceed. The resulting reaction mixture is worked up in conventional manner to yield the compound of formula I.

The thiophosphoric acid amine esters of formula I obtained in accordance with the invention are oils which can be distilled in a high vacuum without decomposition. When they are produced in accordance with the processes a) and b) described above, the same ratio of the cis with respect to the trans isomer thereof in the crotonic acid radical is obtained as is present in the starting materials of formulae V and VI and hence II respectively. The compound I are soluble in organic solvents and may be readily emulsified with water.

The compounds of formula I are useful pesticides. More particularly, the compounds possess insecticidal, acaricidal and nematocidal properties. They are effective against chewing and sucking insects, particularly against spider mites.

The compounds have a low level of toxicity in warm-blooded animals. The new compounds are therefore indicated for use as pesticides in, for example, inhabited rooms, cellars, attics and stables, and for the pro-

tection of plants and animals against noxious organisms, e.g., insects, mites and nematodes.

The combatting of noxious organisms may be carried out by conventional methods, e.g. by treating the subjects or locus to be protected with a composition containing a compound of formula I as active agent. For use as pesticides, e.g. in plant protection, the compounds of formula I may be added to carrier materials to form dusting or spraying agents, e.g., solutions or dispersions, employing water or suitable organic solvents, e.g., alcohol, petroleum or tar distillates, optionally in combination with emulsifying agents, e.g., liquid polyglycol ethers derived from high molecular weight alcohols, mercaptans or alkyl phenols with an alkylene oxide. Suitable organic solvents such as ketones, aromatic, optionally halogenated hydrocarbons, or mineral oils, may also be added as solution aids.

Spraying and dusting agents may contain the usual inert carrier materials, e.g., talc, diatomaceous earth, bentonite, pumice, or other additives such as cellulose derivatives and the like, as well as conventional wetting agents and adhesives.

The compounds of formula I may be present in compositions as mixtures with other known active materials. The compositions may contain between 2 and 90 %, preferably between 5 and 50 % by weight of active agent. For application, the compositions, which may be in diluted form, may contain between 0.02 and 90 %, preferably between 0.1 and 20 % by weight of the compound of formula I.

It should be understood that it is not essential that the compounds of formula I be free from the trans isomer thereof for use in pesticidal compositions. This is pertinent in the case wherein in the process of production of the compounds of formula I, a certain amount of trans isomer thereof is also produced.

The following examples are illustrative of concentrates containing a compound of formula I as active pesticidal agent.

a. 25 parts by weight of a compound of formula I are mixed with 25 parts by weight of isoctylphenyl-decaglycol ether and 50 parts by weight of xylene, whereby a clear solution is obtained, which can easily be emulsified in water. The concentrate is diluted with water to the desired concentration before use.

b. 25 parts by weight of a compound of formula I are mixed with 30 parts by weight of isoctyl-phenylcataglycol ether and 45 parts by weight of a petroleum fraction having a B.P. of 210-280° (D₂₀ = 0.92). The concentrate is diluted with water to the desired concentration before use.

c. 50 parts by weight of a compound of formula I are mixed with 50 parts by weight of isoctylphenylcataglycol ether. A clear concentrate is obtained, which may be readily emulsified in water and which is diluted with water to the desired concentration before use.

The following application examples illustrate the effectiveness of the compounds of formula I.

Insecticidal effect against *Bruchidius obtectus* (bean weevil) - contact effect

0.1 to 0.2 cc of an emulsion containing 0.0125 % of the active agent of formula I are sprayed with a spraying nozzle into a number of 7 cm diameter Petri dishes. The emulsion in the dishes is then dried for about 4 hours, and then *Bruchidius* images are placed in each

dish which is covered with a lid of fine mesh brass wire grating. The animals are kept without food at room temperature.

After 48 hours the rate of mortality is determined. The mortality rate is indicated as a percentage. 100 % means that all the bean weevils were killed, 0 % means that no bean weevil was killed. The evaluation is given in the following Table 1.

TABLE 1

Active agent	Rate of mortality in percent after 48 hours

35	100
40	100

40 Insecticidal effect against *Ephestia Kuehniella* (flour moth) - contact effect

Petri dishes having a diameter of 7 cm, each containing 10 caterpillars of 10 to 12 mm length, are sprayed by means of a spraying nozzle with 0.1 to 0.2 cc of an emulsion containing 0.05 % of the active agent of formula I. The dishes are then covered with a lid of fine mesh brass wire grating. After drying, a wafer is given as food and renewed as required. After 5 days the rate of mortality is determined as a percentage by counting out the live and dead animals. 100 % means that all the caterpillars were killed, 0 % means that no caterpillar was killed. The evaluation is indicated in the following Table 2.

TABLE 2

Active agent	Rate of mortality in percent after 5 days

Insecticidal effect against *Carausius morosus*
(Indian rod locust) - feed effect

Tradescantia branches are immersed for 3 seconds in an emulsion containing 0.0125 % of a compound of formula I. After drying, each of the Tradescantia branches is inserted into a small glass tube filled with water, and this is placed in a glass dish. 10 *Carausius* larvae in the second stage of development are counted into each dish which is then closed with a wire mesh lid.

After 5 days the rate of mortality is determined by counting out the live and dead animals. The mortality rate is indicated as a percentage. 100 % means that all the rod locusts were killed, 0 % means that no rod locust was killed. The evaluation is indicated in the following Table 3.

Insecticidal effect against *Aphis fabae*
(black bean aphid) - contact effect

Broad bean plants (*Vicia faba*) are sprayed to run off with a spraying liquor containing 0.0125 % of active agent. The broad bean plants are strongly infected with all the forms of development of the black bean aphid (*Aphis fabae*).

After 2 days the rate of mortality is determined. The mortality rate is indicated as a percentage. 100 % means that all the bean aphids were killed, 0 % means that no bean aphid was killed. The evaluation is indicated in the following Table 4.

Nematocidal effect against *Panagrellus redivivus*
(paste nematode)

1 cc of an aqueous suspension of *Panagrellus redivivus*, containing about 120 nematodes, is placed in a small cup having a diameter of 5.5 cm and a height of 3.2 cm, and containing 7 g of Terralite. 1 cc of an emulsion containing a compound of formula I is then spread over the Terralite. After 48 hours the contents of the cup are examined in accordance with Baermann's extraction method (G.Baermann, Meded.Geneesk.Lab.-Weltevreden 1917, 41-47), and the live nematodes are counted out under a binocular magnifying glass. The rate of mortality is indicated as a range of 0 to 9 (9 = maximum effect, no live nematodes, 0 = no effect, over 100 live nematodes). The evaluation is indicated in the following Table 5.

The following Examples illustrate the production of the compounds, but in no way limit the scope of the invention. The temperatures are indicated in degrees Centigrade.

EXAMPLE 1: 0-(1-Carboisopropoxy-1-propen-2-yl)-0-methyl-N-ethyl-phosphorothioamide (process a)

185.5 g (1 mol) of tri-n-butylamine are added to a mixture of 144.2 g (1 mol) of acetoacetic acid isopropyl ester and 178 g (1.05 mols) of thiophosphory chloride while stirring and cooling to about -3° during the course of 1 hour. The solution which turns viscous is stirred at 0 to 3° for a further half hour, whereby the solution is mixed as thoroughly as possible. As soon as a viscous oil starts to separate, 20 cc of toluene are added. 1.2 liters of petroleum ether are added, the mixture is stirred for a short period and the tributyl ammonium chloride is filtered off. The filtrate is concentrated in a vacuum at a bath temperature of 30° . 128 g (4.0 mols) of methanol are added to the residue as rapidly as possible at 0° and the mixture is stirred at 0° for 4 hours. 226 g of a 70 % aqueous solution of ethylamine (3.5 mols) are then added at -5° within one-half hour, and the mixture is stirred at 0° for a further one-half hour. The reaction mixture is extracted twice in a separatory funnel with 120 cc amounts of approximately 10 % hydrochloric acid (25 cc of concentrated hydrochloric acid with 100 g of crushed ice). The separation of the phases during the first washing with aqueous hydrochloric acid is effected without the addition of petroleum ether; petroleum ether is preferably added during the second washing with aqueous hydrochloric acid in order to complete the separation. The petroleum ether phase is again washed with water and with hydrogen carbonate solution, is dried with sodium sulphate, and the solvent is removed. The resulting 0-(1-carboisopropoxy-1-propen-2-yl)-0-methyl-N-ethyl-phosphorothioamide has a B.P. of $87-89^{\circ}/5.10^{-3}$ mm of Hg. $n_D^{20} = 1.495$.

Analysis: $C_{10}H_{20}NO_4PS$ Molecular weight: 281.3
Calculated: C 42.7 H 7.2 N 5.0 P 11.0 S 11.4 %

Found: 42.1 6.8 5.3 11.0 10.9 %

EXAMPLE 2: 0-(1-Carboisopropoxy-1-propen-2-yl)-0-ethyl-N-n-propyl-phosphorothioamide (process a)

286.7 g (1 mol) of cis-0-ethyl-0-(1-carboisopropoxy-1-propen-2-yl)-thiophosphorochloridate [$Cl(C_2H_5O)P(S)OC(CH_3)=CHCOOCH(CH_3)_2$], dissolved in 1 liter of toluene, are added to a mixture of 59.1 g (1 mol) of propylamine and 101.2 g (1 mol) of triethylamine at a reaction temperature of 20° with 2 hours. The reaction mixture is stirred at 20° for a further 36 hours, and the precipitated triethylamine hydrochloride is subsequently filtered off. The filtrate is washed with water, dried, the solvent is removed by evaporation, and the resulting product is distilled in a vacuum. 0-(1-Carboisopropoxy-1-propen-2-yl)-0-ethyl-N-n-propyl-phosphorothioamide has a B.P. of $87-89^{\circ}$ at a pressure of 5.10^{-3} mm of Hg. It is obtained almost exclusively with the cis form in the crotonic acid radical. $n_D^{20} = 1.489$.

Analysis: $C_{12}H_{24}NO_4PS$ Molecular weight: 309.4
Calculated: C 46.6 H 7.8 N 4.5 P 10.0 S 10.4 %

Found: 46.7 7.8 4.8 9.9 10.6 %

The 0-ethyl-0-(1-carboisopropoxy-1-propen-2-yl)-thiophosphorochloridate, required as starting material, may be produced as follows:

277.1 g (1 mol) of cis-0-(1-carboisopropoxy-1-propen-2-yl)-thiophosphorodichloridate are added at a reaction temperature of -5° to 276 g (6 mols) of ethanol. The temperature is then allowed to rise to $10-12^{\circ}$, and the mixture is kept at this temperature for one-half hour. The reaction mixture is subsequently diluted with 500 cc of toluene and is made neutral with 200 cc of a 20 % caustic soda solution at -10° to -5° while stirring vigorously. The reaction mixture is added to 200 cc of ice water, the organic phase is separated, is washed well with a sodium hydrogen carbonate solution and subsequently with water, is dried with magnesium sulphate, filtered and concentrated by evaporation in a vacuum at 40° . The resulting product may be purified by distillation in a high vacuum. It is also possible to use the crude product in the reaction for the production of the corresponding compound of formula I.

0-(1-Carboisopropoxy-1-propen-2-yl)-thiophosphoro-dichloridate is obtained in the following manner:

10 105 g (1.03 mols) of triethylamine are added at 10° while stirring within one-half hour to a mixture of 169.4 g (1 mol) of thiophosphory chloride, and 144.2 g (1 mol) of acetoacetic acid isopropyl ester, whereby triethylamine hydrochloride precipitates. The reaction mixture is subsequently stirred at a temperature between -10° and $+10^{\circ}$ for one-half hour, and at 30° for 15 minutes. 500 cc of chloroform are then added to the reaction mixture, this is washed, and after drying the solvent is removed in a water pump vacuum at a bath temperature of 50° . The compound may be used for the next reaction either as crude product or after distillation.

EXAMPLE 3: O-(1-Chloro-1-carbethoxy-1-propen-2-yl)-0-methyl-N-n-propyl-phosphorothioamide (process b)

320 g (1 mol) of 0-(1-chloro-1-carbethoxy-1-propen-2-yl)-N-n-propyl-phosphoramidochlorothionate [$Cl-(n-C_3H_7NH)P(S)OC(CH_3)=CClCOOC_2H_5$] (ratio cis:trans = 9:1) are dissolved in a mixture of 500 cc of toluene and 500 cc of chloroform. A mixture of 32.1 g (1 mol) of methanol and 101.2 g (1 mol) of triethylamine is added at 0° to this solution within 2 hours. The reaction mixture is then stirred at 0° for 5 hours, and subsequently at 20° for 100 hours. The precipitated triethylamine hydrochloride is filtered off and the filtrate is washed, dried and distilled. The resulting 0-(1-chloro-1-carbethoxy-1-propen-2-yl)-0-methyl-N-n-propyl-phosphorothioamide has a B.P. of 107° at 0.01 mm of Hg. The ratio of the cis:trans isomers in the crotonic acid radical amounts to 9:1.

$n_D^{20} = 1.510$.

Analysis: $C_{10}H_{19}ClNO_4PS$ Molecular weight: 315.8
Calculated: C 38.0 H 6.1 Cl 11.2 N 4.4 P 9.8 18S 10.2 %

Found: 38.4 6.3 11.5 4.4 9.7 10.8 %

The 0-(1-chloro-1-carbethoxy-1-propen-2-yl)-N-n-propyl-phosphoramidochlorothionate, required as starting material, may be produced in the following manner:

A solution of 297.5 g (1 mol) of 0-(1-chloro-1-carbethoxy-1-propen-2-yl)-thiophosphorodichloridate

in 1 liter of toluene is reacted at 0° with a mixture of 59.1 g (1 mol) n-propylamine n-orpoylamine and 102 g (1 mol) of triethylamine during the course of 1 hour. The reaction mixture is subsequently stirred at 0° for one-half hour, and at 20° for 1 hour. The precipitated triethylamine hydrochloride is subsequently filtered off, the filtrate is washed with water, dried with sodium sulphate and distilled.

0-(1-Chloro-1-carbethoxy-1-propen-2-yl)-thiophosphorodichloride may be obtained in a manner analogous to the dichloride described in Example 2.

The following compounds (see Table which follows) of formula I,

wherein X signifies a hydrogen atom, which are obtained as a mixture with the trans isomer in some cases, the ratio of the cis:trans isomers in the crotonic acid radical being substantially the same as that of the starting materials, may be obtained in a manner analogous to that described in Examples 1, 2 and 3.

What is claimed is:

1. A compound of the formula:

wherein R_1 is alkyl of one to four carbon atoms, R_2 is alkyl of one to four carbon atoms, R_3 is alkyl of one to five carbon atoms, and X is hydrogen, chlorine or bromine, in which $-\text{CH}_3$ is cis to the $-\text{COOR}_3$ in the crotonic acid moiety.

2. The compound of claim 1, wherein R_1 is methyl, R_2 is methyl, R_3 is isopropyl and X is hydrogen.

3. The compound of claim 1, wherein R_1 is methyl, R_2 is ethyl, R_3 is methyl and X is hydrogen.

4. The compound of claim 1, wherein R_1 is methyl, R_2 and R_3 are ethyl and X is hydrogen.

5. The compound of claim 1, wherein R_1 is methyl, R_2 is ethyl, R_3 is isopropyl and X is hydrogen.

6. The compound of claim 1, wherein R_1 is methyl, R_2 is n-propyl, R_3 is methyl and X is hydrogen.

7. The compound of claim 1, wherein R_1 is methyl, R_2 is n-propyl, R_3 is ethyl and X is hydrogen.

8. The compound of claim 1, wherein R_1 is methyl, R_2 is isopropyl, R_3 is methyl and X is hydrogen.

9. The compound of claim 1, wherein R_1 is methyl, R_2 and R_3 are isopropyl and X is hydrogen.

10. The compound of claim 1, wherein R_1 is ethyl, R_2 is methyl, R_3 is ethyl and X is hydrogen.

11. The compound of claim 1, wherein R_1 is ethyl, R_2 is isopropyl, R_3 is methyl and X is hydrogen.

12. The compound of claim 1, wherein R_1 is ethyl, R_2 and R_3 are isopropyl and X is hydrogen.

13. The compound of claim 1, wherein R_1 is n-propyl, R_2 is methyl, R_3 is isopropyl and X is hydrogen.

14. The compound of claim 1, wherein R_1 is isopropyl, R_2 is methyl, R_3 is ethyl and X is hydrogen.

15. The compound of claim 1, wherein R_1 is methyl, R_2 is n-propyl, R_3 is ethyl and X is chlorine.

16. A compound of claim 1 in which R_3 is isopropyl and X is hydrogen.
